UNITED STATES PATENT OFFICE.

HARRY R. GEER, OF JOHNSTOWN, PENNSYLVANIA.

REVERSING APPARATUS FOR REGENERATIVE REVERSING FURNACES.

1,307,004.

Specification of Letters Patent. Patented June 17, 1919.

Application filed June 22, 1918. Serial No. 241,418.

To all whom it may concern:

Be it known that I, HARRY R. GEER, a resident of Johnstown, Cambria county, Pennsylvania, have invented a new and useful Improvement in Reversing Apparatus for Regenerative Reversing Furnaces, of which the following is a full, clear, and exact description, reference being had to the accompanying drawings, forming part of this specification, in which—

Figure 1 is a plan view partly diagrammatic of an apparatus embodying my invention;

Fig. 2 is a similar view with the parts in reversed positions;

Fig. 3 is a side elevation;

Fig. 4 is a vertical section taken on the line IV—IV of Fig. 1; and

Figs. 5 and 6 are detail views of certain of the parts hereinafter more fully described.

My invention has relation to reversing apparatus for regenerative reversing furnaces, and is designed to provide a simple and effective apparatus of this character which can be readily installed and operated.

The nature of my invention will be best understood by reference to the accompanying drawings, in which I have shown the preferred embodiment thereof and which 30 will now be described, it being premised, however, that various changes can be made in the details of construction, arrangement and combination of the parts without departing from the spirit and scope of the invention as defined in the appended claims.

In these drawings, the numeral 2 designates a circular base or floor plate through which open upwardly the outer ends of the gas ports 3 and 3^a, leading through the usual 40 regenerators to opposite ends of the furnace, the air ports 4 and 5, leading to the respective air regenerators, and the central port 6, leading to the stack connection 7. The openings in the base or floor plate, which communicate with the gas and air ports, are arranged symmetrically around the opening leading to the stack port 6, with their centers 90° distant from each other.

8 designates a connector, by means of 50 which either the ports 3 and 5 or the ports 3^a and 4 may be placed in communication with the port 6. This connector is in the form of a hollow hood having two branches 8^a and 8^b, at right angles to each other, and 55 both communicating interiorly with the central portion of the hood. This hood or con-

nector is set upon the base or floor plate 2, being preferably provided with a base ring 8^c, in the form of a casting which forms the seating on said plate, and which is arranged 60 to slide upon the upper surface of the plate as the connector is moved from one position to another in the manner hereinafter described.

9 designates a connector for reversing the 65 gas flues 3 and 3^a. This connector is in the form of an elbow having its vertical arm resting on the plate 2, and its horizontal arm supported on the central portion of the connector 8. For the purpose of this support 70 and also to provide means for the rotary movement of both connectors, a turn table or plate 10 is mounted on antifriction bearings 11, on the top of the connector 8, and the horizontal arm of the elbow 9 has a convex 75 rib 12, seating in a groove 13 in said plate. In this manner, either or both connectors may be rotated about a common vertical center and the connector 9 may also rock somewhat upon the bearing provided by the rib 80 12. The lower end of the vertical arm of the connector 8 is provided with a seating ring 14 which preferably consists of a casting and which has a loosely fitted joint connection with the elbow. This joint is sealed, and the 85 ring is also cooled by providing it with an external water trough 15, into which a sealing flange 16 of the connector 9 depends. This water trough is provided with an overflow pipe 17, which may be discharged at 90 any suitable point, as into the curved stationary trough 18, over or in which the end of the overflow pipe travels as the connector is moved.

19 designates the gas supply pipe which 95 leads into a dome 20, which is supported centrally over the superimposed portions of the connectors 8 and 9, and which preferably has a water-sealed joint 21, with the horizontal arm of the connector 9, with which it 100 communicates. 22 is a damper for controlling the flow of gas from the supply pipe and dome into the connector 9.

23 designates a damper plate for the air ports. This damper plate is suspended from 105 a rope or cable 24 from any suitable overhead point, the rope or cable passing through a guide 25 on the arm 26, which is rigidly secured to the hub portion of a pulley 27. This pulley is arranged to be rotated by any 110 suitable connection with the connector 9. In the arrangement illustrated, the vertical arm

of the latter is provided with a peripherally grooved sector 28, fixed thereto. A belt 29 (shown in dotted lines in Figs. 1 and 2) is connected at its ends to the respective ends 5 of the sector 28, its intermediate portion lying in the groove of the sector and its two branches crossing each other and passing around the pulley 27.

For the purpose of shifting the connectors 10 8 and 9, and at the same time actuating the damper plate 23, I provide the mechanism now to be described.

30 designates an electric motor, whose armature is arranged to drive a shaft 31. 15 This shaft is, in turn, arranged to drive a sleeve 32, mounted thereon, through either one of two reversely acting clutches 33 and 34. The sleeve 32 is provided with a worm 35, which meshes with peripheral teeth on 20 the outer circumference of the circular rack 36. This rack is seated around the circular base plate 2, upon suitable antifriction bearings, such as the antifriction rollers 37. The motor 30 is a reversible type motor, and 25 when operating in one direction will drive the sleeve 32 and worm 35 through the clutch 33. When operating in the reverse direction, it will drive said sleeve and worm through the reversely acting clutch 34. 30 Each of these clutches is normally held in engaging position by a suitable spring 38. 39 and 40 designate clutch shifters which are arranged to be automatically operated to release their respective clutches by the 35 action of the cam projections 41 and 42 on the circular rack.

In Fig. 1, the clutch 33 is shown as held in its released position by the action of the cam 42, upon the clutch shifter 40, while 40 the clutch 34 is shown engaged.

The circular rack is provided with means for engaging the connectors 8 and 9, respectively, at the proper times and shifting them from one position to another. In the arrangement shown, the outer end of the connector 45 9 has secured thereto a double-ended bolt 43, (shown in detail in Fig. 5) whose end portions, respectively, engage the shoes 44. These shoes are engaged by springs 45, on 50 the bolt, and each of them is provided with a depending lug 46, adapted for engagement with the pivoted tappets or latches 47 and 48, which are pivotally connected to the circular rack. The outer end of each of the 55 arms 8^a and 8^b of the connector 8 is provided with a single spring shoe 49, adapted to be engaged, respectively, by fixed lugs 50 and 51, which are mounted on said circular rack. 52 designates a tripping bar, which is secured to the floor plate 2, and which has beveled end portions (see Figs. 5 and 6) which are adapted to engage the heel portions of the tappets or latches 47-48, and trip them out of engagement with the 65 shoes 44.

In the position of the parts shown in Fig. 1, gas is passing from the dome 20 through the connector 9 into the gas port 7, and thence to the gas regenerator and furnace. The return gas port is connected to the stack 70 port 6, through the arm 8^b of the connector 8. Air is entering the open upper end of the air port 4, below the damper plate 23, and the return air port 5 is connected to the stack port 6, through the arm 8^b of the connector 8. 75

It being desired to reverse the furnace the motor 30 is actuated to turn the circular rack bar in an anticlockwise direction. As the rack bar commences to rotate, the tappet 80 or latch 47 engages the shoe 44 of the connector 9 in the manner shown in Fig. 5, and thereby causes said connector to rotate. This rotary movement of the connector continues until the tappet 47 engages the trip 85 52, and thus releases it from engagement with the shoe 44. At this time, in the arrangement shown, the connector 9 has been rotated through an angle of about 45° to the position shown in dotted lines in Fig. 1, intermediate the ports 3 and 3^a. This movement of the connector 9 through the connections before described swings the damper plate 23 from the position shown in full lines in Fig. 1 to the position shown in dotted lines 90 therein. At this time, the fixed lug 50 on the rack bar engages the shoe 49 on the outer end of the branch 8^a of the connector 8; and the connector 8 is rotated through an angle of 180° until it is brought to the 100 position shown in Fig. 2, where its branches 8^a and 8^b, respectively, connect the gas port 3 and air port 4 with the stack port 6. At the time the connector 8 begins the last 45° of its movement, the lug 51 will engage the 105 lug 46 of the other shoe 44 of the connector 9 and will complete the shifting movement of this connector by carrying it to the position shown in full lines in Fig. 2. In this position, it connects the dome 20 with the 110 gas port 3^a. When the parts have assumed these fully shifted positions, the clutch shifter 39 will be actuated to throw out the clutch 34 and stop further movement of the circular rack. The parts are now left in 115 such position that, upon the reversal of the motor 30, to rotate the circular rack in the opposite direction, the two connectors will be shifted back to the positions shown in Fig. 1, in a manner that will be readily understood from the foregoing, the connector 9 being first moved to a midway position and left there before the connector 8 commences its shifting movement. 120

During each reversal, the circular rack 125 bar has a circular movement of 270°, the connector 9 being moved to its intermediate position during the first 45° of such movement. The shifting movement of the connector 8 commences when the circular rack 130

bar is rotated through 90°, and continues for 180°, and the final shifting of the connector 9 takes place during the last 45° of this movement.

5 By this arrangement, it will be seen that at each reversal, the supply of gas is first shut off before reversal takes place, and air is allowed to sweep into the furnace through the air and gas ports at the inlet end of 10 the furnace. This gives an opportunity for the gas, which has passed the reversing apparatus, to be consumed before the reversal takes place. This, of course, results in a considerable saving of gas which would otherwise be lost at each reversal. It will also be noted that, while of course the direction 15 of flow of the gas and air is reversed in the gas and air ports in the usual manner, yet the flow within the reversing apparatus is 20 always in the same direction. That is to say, the return gases from the furnace are always passing upwardly into the connector 8 and downwardly into the stack port, while the entering gas always flows downwardly 25 through the connector 9 into one of the gas ports. This makes possible a very simple and convenient arrangement of the ports at the reversing apparatus.

The connector 8 has a three-point support upon the base or floor plate 2, and can readily be shifted on said plate from one position to the other. The rocking end of the support of the connector 9 upon the connector 8 permits both connectors to have sufficient freedom of movement to adapt them- 30 selves to any irregularities of the surface of the floor plate which may occur from warping or other causes. The entire reversing operations can be carried out by the use of 35 a single motive device and by the mere closing of the supply circuit of such device.

It will be obvious that various changes may be made in the driving connections between the motor and the circular rack bar; 40 that the construction and arrangement of the latter may be widely changed; that any suitable means may be provided for engaging and disengaging the connectors at the proper times; that the construction and arrangement of the connectors themselves may be changed; and that various other changes 45 can be made within the scope of the appended claims.

I claim:

55 1. Reversing mechanism for reversing regenerative furnaces, comprising a rotary connector for reversing the gas supply and another rotary connector for reversing the return connections of the furnace, the last 60 named connector having two converging radial branches, substantially as described.

2. Reversing mechanism for reversing regenerative furnaces, comprising a rotary connector for reversing the gas supply and 65 another rotary connector for reversing the

return connections of the furnace, the last named connector having two converging radial branches, together with actuating means for effecting different shifting movements of the two connectors, substantially 70 as described.

3. Reversing mechanism for reversing regenerative furnaces, comprising a rotary connector for reversing the gas supply and another rotary connector for reversing the 75 return connections of the furnace, together with actuating means for giving the gas-reversing connector an interrupted shifting movement and for giving the other connector a continuous shifting movement, sub- 80 stantially as described.

4. Reversing mechanism for reversing regenerative furnaces, comprising a rotary connector for reversing the gas supply and another rotary connector for reversing the 85 return connections of the furnace, together with actuating means for said connectors, said means having devices for first partially shifting the gas-reversing connector to shut off without reversing the gas supply and to 90 then shift the other connector and to complete the shifting movement of the gas-reversing connector, substantially as described.

5. In furnace-reversing apparatus, the combination with gas and air ports, a stack port 95 and a gas supply conduit, of a rotary connector arranged to shift the gas supply from one of the gas ports to the other of said ports, a second connector having two converging radial branches which are arranged 100 to connect the stack port with one of the gas ports and air ports in one position and with the other gas port and the other air port in another position, said connectors being arranged to rotate about a common vertical axis, and means for actuating the same, 105 substantially as described.

6. In furnace-reversing apparatus, the combination with gas and air ports, a stack port and a gas supply conduit, of a rotary 110 connector arranged to shift the gas supply from one of the gas ports to the other of said ports, and a second connector having two converging radial branches which are arranged to connect the stack port with one 115 of the gas ports and air ports in one position and with the other gas port and the other air port in another position, said connectors having superimposed portions and being arranged to rotate about a common 120 vertical axis, together with means for actuating said connectors, substantially as described.

7. In furnace-reversing apparatus, the combination with gas and air ports, a stack 125 port and a gas supply conduit, of a rotary connector arranged to shift the gas supply from one of the gas ports to the other of said ports, and a second connector arranged to connect the stack port 130

- with one of the gas ports and air ports in one position and with the other gas port and the other air port in another position, said connectors having superimposed portions and being arranged to rotate about a common vertical axis, together with means for actuating said connectors, said actuating means having devices whereby the gas-reversing connector is first shifted to shut off without reversing the gas supply and to then move the other connector and to complete the movement of the gas-reversing connector to reverse the furnace, substantially as described.
- 15 8. In furnace-reversing apparatus, the combination with gas and air ports, a stack port and a gas supply conduit, of a connector having two converging radial branches, which in one position connect one of the air ports and one of the gas ports with the stack port and in the other position connect the other air and gas ports to said stack port, a gas supply reversing connector having an inlet portion arranged between the first named connectors and the gas supply conduit, and means whereby said connectors may be rotated about a common vertical axis, substantially as described.
- 20 9. Reversing mechanism for reversing furnaces, comprising a rotary connector for reversing the gas supply, another rotary connector for shifting the return connections from the furnace, the last named connector having two convergent radial branches, a single motive device, and actuating connections between said device and the said connectors, substantially as described.
- 25 10. Reversing mechanism for reversing furnaces, comprising a rotary connector for reversing the gas supply, another rotary connector for shifting the return connections from the furnace, a single motive device, and actuating connections between said device and the said connector, said connections including means whereby the gas-reversing connector is first moved to cut off without reversing the supply of gas and the two connectors are then moved to complete the reversal of the furnace, substantially as described.
- 30 11. In reversing apparatus for regenerative reversing furnaces, the combination of a branched connector constructed and arranged in each of two different positions to connect an air and a gas port with a stack port, of a separate gas supply reversing connector of elbow form, the latter having a horizontal arm provided with a rocking and rotatable bearing upon the top of the first named connector, substantially as described.
- 35 12. In furnace-reversing apparatus, the combination with a floor plate having port

openings extending vertically therethrough, said openings comprising a central opening leading to a stack port, two other openings communicating with gas ports and two other openings communicating with air ports, of a connector mounted to rotate on the floor plate and adapted in each of two positions to connect the stack port and one of the air and gas ports, a gas supply reversing connector also mounted to turn on the floor plate, and means for actuating said connectors to shift them from one position to another, substantially as described.

13. In furnace-reversing apparatus, the combination with a floor plate having port openings extending vertically therethrough, said openings comprising a central opening leading to a stack port, two other openings communicating with gas ports and two other openings communicating with air ports, of a connector mounted to rotate on the floor plate and adapted in each of two positions to connect the stack port and one of the air and gas ports, a gas supply reversing connector also mounted to turn on the floor plate, and means for actuating said connectors to shift them from one position to another, the actuating means having devices whereby the gas supply connector may be partially shifted to cut off without reversing the gas supply before the other connector is moved, substantially as described.

14. In furnace-reversing apparatus, the combination with two separate connectors mounted for independent rotation, one of said connectors having means for reversing the gas supply to the furnace and the other of said connectors being arranged to reverse the air supply and return connections of the furnace, of a rotary member having means for engaging and moving the said connectors, and a reversible motor for actuating said movable member, substantially as described.

15. In furnace-reversing apparatus, the combination with two separate connectors mounted for independent rotation, one of said connectors having means for reversing the gas supply to the furnace and the other of said connectors being arranged to reverse the air supply and return connections of the furnace, of a rotary member having means for engaging and moving the said connectors, and a reversible motor for actuating said movable member, together with automatically actuating clutch means for stopping the movement of said movable member at the proper times, substantially as described.

In testimony whereof, I have hereunto set my hand.

HARRY R. GEER.
